UNITED STATES PATENT OFFICE.

HILAIRE J. COMEAU, OF HARTFORD, CONNECTICUT.

COLLAR-FASTENER.

1,221,290.

Specification of Letters Patent.

Patented Apr. 3, 1917.

Application filed April 13, 1911. Serial No. 620,841.

To all whom it may concern:

Be it known that I, HILAIRE J. COMEAU, a citizen of the United States, residing in the city of Hartford, county of Hartford, State of Connecticut, have invented certain new and useful Improvements in Collar Fasteners, of which the following is a specification, reference being had to the accompanying drawings, forming a part hereof.

10 My invention relates to those articles for manufacture usually called collar buttons but is in the nature of a collar holder or clip, and may be properly styled a collar fastener. Among the objects of my invention are the production of an article of this character which will not constitute a projection or protuberance tending to press against the back of the neck and to likewise avoid the protuberance of the usual collar button projecting outwardly and which is frequently pressed by the outer or overhanging portion of a turned-down collar, forcing the collar button unpleasantly and sometimes dangerously against the back of the neck. More particularly my object is to produce a collar fastener avoiding usual objections, but at the same time one which can be most readily inserted in the collar and likewise easily attached in its normal position, and which at the same time will not slip out of its engagement during the operation of attachment nor which can be released when in normal position, will avoid all interference with a cravat, and will when in use hold the engaging parts securely and neatly in the desired position. It may be especially emphasized that the adjustment of my collar fastener does not involve any difficult operation nor an operation which 40 would injure the collar or the device; while the above and other advantages will appear as hereinafter set forth and in the practice of my invention.

In the accompanying drawings I have illustrated an embodiment of my invention and its method of attachment, with certain modifications as to detail and form, which will hereinafter be more fully described and in which:

50 Figure 1 is a view in perspective of the fastener in place, with the collar and neck band of the shirt partially in section, and illustrates the flatness or closeness with which the collar is secured to the shirt band. 55 Fig. 2 is a perspective view of the fastener.

Fig. 3 is a fragmentary view of the collar from the back with a portion broken out, showing how the fastener completely fills the button hole and is held firmly in the collar.

The device is formed of sheet metal and as shown in Fig. 2 A is a main or body part having a bend *a* at its lower extremity from which extends upward the part B, the upper extremity of part A is bent in the opposite direction at *c* and has a downwardly extending part C, the lower edge of which is flush with the bend *a* between parts A and B; part B extends upwardly beyond the bend *c* for reasons hereinafter described, the device being very flat and compact, leaving only sufficient space between the body A and the upwardly extending portion B to allow the free passage of the downwardly extending part *e'* of the pocket *e* of the neck band E, while the space between parts A and C will hold the collar snugly.

In practice the part C is pushed through the button hole of collar D and the bend *c* brought to rest in the button hole, and because of the snug fit of the collar between parts A and C there is no lateral motion between the fastener and the collar and the upper surface of bend *c* is held in contact with the upper edge of the button hole, thus preventing any tendency for the fastener to become dislodged and fall out.

The starched condition of the collar on the upper edge of the button hole affords a positive abutment against which the bend *c* engages, and this is true to such an extent that a positive, direct pressure must be exerted against the upper edge of the button hole to press it aside sufficiently to permit the extraction of the holder or button, or "clip" as it may be called. The portion of the collar below the button hole being stiff and the space between the bands A and C being just sufficient to take the thickness of the collar, a button or clip made in accordance with my invention has no tendency to fall out nor can it be forced out in any conditions of use when in position. The free upturned part B is now clipped under the downwardly turned flap *e'* of pocket *e* and pressed upward until edge *b* contacts with the bottom of said pocket, thus preventing any further upward movement of the collar but allowing circumferential movement of the collar with respect to the neck band due to the elongated pocket *e*.

The advantages of the improved device include simplicity, durability and cheapness of construction, ease of adjustment and freedom from any frictional or binding effect

5 on the tie when being adjusted, as well as the freedom from annoyance experienced when the closing of the collar in front is not centrally located, which latter may be due to an improper placing of the button 10 hole in the collar or shirt band at the back or distortion of either or both the collar or neck band in ironing.

15 Of especial importance is the ease and simplicity with which my holder or button can be affixed to the collar, and when on 20 remains fixed, until voluntary removal which is equally simple and easy.

Where the collar has but one fixed point 25 of attachment to the neck band and that at the closing point in front, it will readily adjust itself to any slight imperfections or irregularities in either, and result in a perfectly setting collar. Other great advantages of my device are the flatness with 30 which the collar is secured to the collar band and the freedom from projections of any kind which cause discomfort to the wearer or interfere with the adjustment of the cravat. While I have illustrated a single form of my device, it is evident that changes

in form and detail may be made within the scope of the claim, without departing from the spirit of my invention or without sacrificing any of its advantages.

What I claim and desire to secure by Letters Patent is:

A collar fastener adapted to secure a collar to a shirt neck-band and to be attached to the collar, comprising a rectangular thin metal band bent transversely and oppositely at two points to form oppositely projecting legs, the one side leg of which extends beyond the adjacent bend, and the other terminating with its adjacent bend, the clearness between said outside legs and the medial section being of a size to closely accommodate the thickness of material in a collar, and the width at the bends being substantially the same as the width of the band, whereby the bend is adapted to snugly 40 fit a button-hole in the collar through which the end passes.

In testimony whereof I have signed my name to this specification at New York city, New York, this 11th day of April, 1911, in 45 the presence of two subscribing witnesses.

HILAIRE J. COMEAU.

DANIEL J. GUINAN,
HERMANN F. CUNTZ.

Correction in Letters Patent No. 1,221,290.

It is hereby certified that in Letters Patent No. 1,221,290, granted April 3, 1917, upon the application of Hilaire J. Comeau, of Hartford, Connecticut, for an improvement in "Collar-Fasteners," an error appears in the printed specification requiring correction as follows: Page 2, line 45, claim, for the word "clearness" read *clearance*; and that the said Letters Patent should be read with this correction therein that the same may conform to the record of the case in the Patent Office.

Signed and sealed this 1st day of May, A. D., 1917.

[SEAL.]

R. F. WHITEHEAD,

Cl. 24--101.

Acting Commissioner of Patents.
